UNITED STATES PATENT OFFICE

1,997,382

GOLF CLUB

Walter S. Howell, Summit, N. J.

Application November 17, 1930, Serial No. 496,184

1 Claim. (Cl. 281—44)

This invention relates to a novel and improved form of golf club having means thereon for readily keeping score. The invention will be best understood from the following description and the annexed drawing, in which I have shown a selected embodiment of the invention, and in which:

Fig. 1 is a view of a golf club handle having my invention applied thereto;

10 Fig. 2 is a view similar to Fig. 1, but showing a slight departure in the form of the club;

Fig. 3 is a perspective view of the end of one of the clubs appearing in Fig. 1 or 2, more particularly Fig. 1;

15 Fig. 4 is a perspective view of the pencil appearing in Figs. 1, 2 and 3;

Fig. 5 shows the front and back of a score card suitable for use on my device;

20 Fig. 6 is a perspective view of a club with the invention applied thereto.

The invention is designed to provide a ready means for keeping score while playing golf, and consists essentially in providing ready means for retaining score cards in position on a club so as to avoid the continual necessity of reaching into the player's pockets for a score card. Another feature involves the provision of means for likewise holding a pencil in convenient proximity to the score card on the club, so that the pencil also will be readily accessible when needed.

While the invention is shown as applied to the grip of a club, it is to be understood that it may likewise be placed in any suitable position, and the word "handle", as used hereafter, should be understood as including not only the grip 1, but also the shaft 2 of the club. In Fig. 1 is shown a grip secured integrally to a shaft, while in Fig. 2 is shown a separate grip 1' which may be secured to a shaft by means of a screw 3. Either form may be used as found most expedient, although the detachable one shown in Fig. 2 may have certain advantages in applying the invention to shafts of clubs in place of the existing grip already on the same club.

45 The handle shown in Figs. 1 and 3 is provided with a metal insert 4 secured in place by screws 4' having a longitudinally extending recess or slot 5, this slot having overhanging edges 6 and 7. The depth of the slot is such that one or more score cards 8 may be slid in at the upper open end 9 of the slot.

Each score card is provided with spaces 10 corresponding to holes, and preferably these spaces are numbered as indicated at 11 in a man-

ner which will be obvious. A score card 8 may be inserted in the open end 9 of a slot, where it will be retained in such position that the spaces 10 will be exposed between the edges 6 and 7. In this position, the numeral designations 11 will be covered up, but on the portion of the handle adjacent the edge 6, for example, is a row of designations 12 registering with corresponding spaces 10 on the card when the card is in place in the slot. Thus it will be seen that the score 10 entered on the card opposite the designations 12 will be placed in the corresponding spaces 10 opposite the designations 11, so that when the score card is removed from the slot it will furnish a permanent record of the score.

15 If a number of cards are used, each card, after having the score marked thereon, may be removed, and this will expose another card placed beneath it, or, if desired, the slot may be made only of sufficient depth to hold one card. The reverse of the card may be used as shown in Fig. 5 to contain the name of the course, together with the name of the player and the date, or any other information which may be desired to preserve. If desired, one or more slots like 5 25 may be placed adjacent each other around the shaft of the club. Any other arrangement of slots may be made to accommodate as many cards as desired.

I also provide means in the insert 4 to hold a 30 pencil 13 which may be provided with the usual eraser 14. This pencil may be received in a hole in the insert, and movement in the hole may be limited by a ledge 15 which will engage the top 35 of the hole. The pencil may be prevented from falling out by any suitable means, such as a spring 16 which is attached to the card holder and arranged to functionally engage the pencil as shown in Fig. 4. Other forms of spring holders may be used if desired.

40 In the form shown in Fig. 2, no insert 4 is used, but instead the slot 5 and hole for the pencil are formed directly in the material of which the grip 1' is made. Otherwise this embodiment closely follows the one described above.

45 While I have shown the invention as embodied in specific forms, it is to be understood that various changes in details may be made without departing from the scope of the invention, and I therefore do not intend to limit myself except by 50 the appended claim.

I claim:

A score card holding device adapted to be mounted on a golf club and substantially cylindrical in form and of a diameter substantially the 55

same as that of a golf club handle, said device having an elongated slot on and extending longitudinally of the cylindrical surface thereof, means for retaining a score card in said slot, said card when in the slot having exposed spaces for the score for each hole, hole designating numerals on said surface along said slot and regis-

tering with the corresponding spaces on a card in the slot, and means to secure said device to a golf club handle with said cylindrical surface forming a substantial continuation of the surface of said handle.

WALTER S. HOWELL.
